ROTARY BAR FASTENER FOR HINGED DOORS

Edward H. Lehman, Chicago, Ill., assignor to
W. H. Miner, Inc., Chicago, Ill., a corporation
of Delaware

Application January 19, 1948, Serial No. 3,095

3 Claims. (Cl. 292—218)

1

This invention relates to improvements in door fasteners of the rotary bar type, especially adapted for doors of refrigerator cars and automobile trucks.

The main object of the invention is to provide a door fastener of the rotary bar type having keeper engaging crank arms at opposite ends provided with crank pins engageable with fixed slotted keepers, wherein the crank pins are outwardly tapered and the slots of the keepers are formed to interfit therewith, whereby the bar is locked against vertical displacement with respect to the keepers, thus locking the door against weaving when it is fastened in closed position by engagement of the crank pins with the keepers.

Other objects of the invention will more clearly appear from the description and claims hereinafter following.

In the accompanying drawings forming a part of this specification, Figure 1 is an elevational view of the end wall of a refrigerator automobile truck, provided with a pair of hinged doors, illustrating my improvements in connection therewith, said view being broken to accommodate the same to the sheet of the drawing. Figure 2 is an enlarged elevational view of the structure shown in Figure 1 at the lower left hand end portion of the right hand door. Figure 3 is a horizontal sectional view through the operating bar, corresponding substantially to the line 3—3 of Figure 2. Figure 4 is a plan view of the lower keeper shown in Figure 2, said view being on a still further enlarged scale. Figure 5 is a front elevational view of Figure 4. Figure 6 is a horizontal sectional view, on an enlarged scale, corresponding substantially to the line 6—6 of Figure 2, with the guide or bearing bracket omitted. Figure 7 is an elevational view, on an enlarged scale, of the lower end member of the rotary operating bar shown in Figure 1, looking from right to left. Figure 8 is a side elevational view of Figure 7.

In said drawings, 10 indicates the rear wall member of a refrigerator automobile truck, provided with a door opening 11, closed by the usual pair of hinged doors 12 and 13. The doors 12 and 13 are supported along their outer edges by hinges 14—14 of well-known design. As is understood by those skilled in this art, the hinged doors 12 and 13 have beveled meeting edges, the edge of the door 12, which is the door last closed, overlapping the adjacent door 13.

My improved door fastener, as shown in the drawings, comprises broadly top and bottom keepers A and B, secured to the wall 10, a vertically disposed rotary operating bar C mounted

2

on one of the doors, top and bottom keeper engaging crank members D—D, and an operating handle lever E for rotating the bar C.

The keepers A and B are of similar design, except as hereinafter pointed out. Each keeper is in the form of a heavy block provided with securing ear portions 15—15 at opposite sides thereof for fastening the same to the wall 10. The keepers A and B are fixed to the wall 10, above and below the doors in vertical alignment. Each keeper has an inwardly directed, outwardly opening cam slot 16 within which the corresponding keeper engaging crank member of the operating bar is engageable. The cam slot 16 is defined by spaced, lateral side walls 17 and 18 and a curved inner end wall 19, extending from one side wall to the other. The side walls of the slot of the lower keeper are upwardly inclined toward each other, as shown most clearly in Figure 5, thus defining a slot of tapered transverse cross section, which contracts upwardly. The slot 16 of the upper keeper is reversely arranged, that is, the keeper is inverted so that the slot is contracted downwardly. The curved end wall of each keeper is also inclined, being directed inwardly with respect to the slot in upward direction in connection with the lower keeper and in downward direction with the upper keeper. The curved end wall of the slot of each keeper is continuous with the inclined side walls of each slot. The two keepers A and B are of the same design, but, as hereinbefore mentioned, are reversely arranged with respect to each other, the top keeper A being inverted with respect to the bottom keeper B so that the slot 16 of the top keeper A opens downwardly and that of the bottom keeper B opens upwardly.

The rotary bar C is preferably of rectangular, transverse cross section and has end members 20—20 secured to the top and bottom end portions thereof, each end member being forked, as indicated at 21, to embrace the bar C, and the end members are secured to the bar by fastening elements, such as rivets 22—22, extending through the forked portions thereof.

Each end member 20 has a keeper engaging crank member D formed at its outer end, comprising a crank arm 23 and a crank pin 24 at the free or outer end of said arm. The bar C is rotatably supported on the door 12 by bearing or guide brackets 25—25, adjacent the top and bottom end portions of said door, and an intermediate guide bracket 26 secured to the outer side of the door. The end members 20—20 have cylindrical bearing portions in the form of short

shafts 21-21 journaled in the brackets 25-25, these shaftlike bearing portions being formed outwardly of the forked portions 21-21 of the end members. The crank pin 24 of each crank member D is tapered toward its outer end, that is, it is of conical formation to snugly fit the tapered slot 16 of the corresponding keeper when engaged therewith to hold the bar C against endwise movement in vertical direction. The crank pins 24-24 of the top and bottom crank members thus have wedging engagement within the slots of the keepers A and B to hold the bar C against vertical movement with respect to said keepers when the door has been forced to closed position by the fastener, thus locking the doors 12 and 13 against weavering.

The tapered keeper engaging crank pin 24 of each crank member is also provided with a relatively narrow, flat locking face section 28, which extends from the inner to the outer end thereof and is adapted to bear flatly on the outer wall 18 of the corresponding keeper when the door is in closed and locked position, thus preventing accidental rotary creeping of the crank pin.

The bar C is operated by the usual handle lever E which may be locked against movement by the usual latch means indicated by 29.

As is well known to those skilled in this art, to open and close the doors, the bar C is rotated by the handle lever E to cam the door 12 outwardly or inwardly through the action of the crank pins 24-24 of the crank members D-D within the slots 16-16 of the keepers. As the bar is rotated to open the door 12, the crank pins 24-24 of the top and bottom crank members are disengaged from the cooperating keepers as the crank pins are leaving the keeper slots, thereby freeing the door 12 to be swung fully open. In rotating the bar C to fasten the door by engagement of the crank pins 24-24 of the crank members D-D within the slots of the top and bottom keepers, the crank pins, due to their tapered formation, wedge tightly into the corresponding tapered slots of the keepers, thereby locking the bar C against vertical displacement.

I claim:

1. In a fastener for a hinged door of a container, the combination with fixed top and bottom slotted keepers on said container above and below the door, the slots of said top and bottom keepers contracting, respectively, downwardly and upwardly; of a vertically disposed rotary operating bar on said door; and top and bottom

keeper engaging members having crank pins engageable within the slots of said keepers, said crank pins being of tapered formation and having wedging engagement within the tapered slots of the keepers to hold said bar against vertical displacement when the fastener is in door locking position.

2. In a fastener for a hinged door of a container, the combination with fixed top and bottom keepers on said container above and below the door, each keeper having a cam slot, the slot of the top keeper being defined by downwardly converging spaced side walls, and the slot of the bottom keeper being defined by upwardly converging spaced side walls; of a vertically disposed rotary operating bar on said door; and top and bottom keeper engaging crank members on said bar having crank pins engageable within the slots of said keepers, said crank pins being tapered off toward their inner ends and having wedging engagement within the slots of said keepers to lock the bar against vertical displacement when the fastener is in door locking position.

3. In a fastener for a hinged door of a container, the combination with fixed top and bottom keepers on said container above and below the door, each of said keepers having an inclined cam slot defined by spaced lengthwise extending side walls, said side walls of the slot of the top keeper converging in downward direction and said side walls of the slot of the bottom keeper converging in upward direction; of a vertically disposed rotary operating bar on said door; and top and bottom crank members on said bar, each of said crank members including a radial arm and a crank pin at the outer end of said arm, each of said crank pins being of conical contour and flared toward its outer or free end to interlock with the converging walls of the slot of the corresponding keeper when engaged within said slot.

EDWARD H. LEHMAN.
